COMBINATION PACKAGE OF CHILDREN'S
PANTIES AND PENCILS

George Gold, Brooklyn, N. Y.

Application December 24, 1949, Serial No. 6,831

Term of patent 7 years

(Cl. D80—5)

To all whom it may concern:

Be it known that I, George Gold, a citizen of the United States, residing at Brooklyn, in the county of Kings and State of New York, have invented a new, original, and ornamental Design for a Combination Package of Children's Panties and Pencils, of which the following is a specification, reference being had to the accompanying drawing, forming part thereof.

Fig. 1 is a front perspective view of a combination package of children's panties and pencils showing my new design.

Fig. 2 is a rear elevational view of Fig. 1.

The broken lines on the drawing are for illustrative purposes only.

I claim:

The ornamental design for a combination package of children's panties and pencils, as shown and described.

GEORGE GOLD.
